UNITED STATES PATENT OFFICE.

CHARLES R. FARGO, OF CHICAGO, ILLINOIS, ASSIGNOR TO WILSON-JONES LOOSE LEAF COMPANY, A CORPORATION OF ILLINOIS.

METHOD FOR FINISHING THE RAW EDGES OF COATED FABRIC OR THE LIKE.

Application filed April 27, 1921. Serial No. 465,071.

To all whom it may concern:

Be it known that I, CHARLES R. FARGO, a citizen of the United States, and a resident of the city of Chicago, in the county of Cook 5 and State of Illinois, have invented certain new and useful Improvements in a Method for Finishing the Raw Edges of Coated Fabric or the like; and I do hereby declare that the following is a full, clear, and exact description of the same, reference being had to the accompanying drawings, and to the numerals of reference marked thereon, which form a part of this specification.

My invention relates to a method for finishing the raw cut edges of pyroxylin coated fabric or the like to give the same a smooth and pleasing appearance. In the manufacture of pyroxylin coated fabric or artificial or substitute leather, a woven fabric or the 15 like is usually covered with a mixture or composition of cellulose or pyroxylin, a drying oil and a solvent, which, after evaporation, leaves a tough elastic and durable film thoroughly impregnated in the fabric. In 20 some instances the fabric is coated with a mixture of pyroxylin, glue, or gum sandarac or shellac and solvents, in other cases nitro-cellulose and rubber composition is used. The artificial leather so manufactured is 25 usually sold to the trade in rolls or sheets and must be cut into blanks of proper size according to the use to which it is intended to be put. When a fabric or the like is used for a cut flush cover, i. e. without turned 30 edges, the sheared edges will appear somewhat fringed or tufted and not smooth, due to the raveled edges of the fabric, and to remedy this objection I have found that the 35 above described compositions will readily fuse and seal the raw sheared ends of the fabric. And it is therefore an object of this 40 invention to provide a simple and efficient method for removing the fringes and sealing the raw edges of the coated or treated fabric. And it is a further object of this 45 invention to provide a novel apparatus for aiding in accomplishing the same. My invention comprises the novel features of procedure and structure hereinafter described 50 and more particularly pointed out in the claims.

In the accompanying drawing, which illustrates a preferred embodiment of this invention, and in which similar reference

numerals refer to similar features in the different views:

Figure 1 is a perspective view of a clamp supporting a stack of sheared imitation leather blanks.

Figure 2 is a section through an individual blank illustrating the fringed or tufted edges at the left, on an enlarged scale.

Figure 3 is a view similar to Figure 2, showing the finished edge, on an enlarged scale.

As shown on the drawings:

In carrying out my method, I first stack a convenient number of cut blanks, the edges of which it is desired to finish, in superimposed relation with the edges in alinement and compress the same. I then apply a torch or the like to the fringed edges to singe the fringes and at the same time heat and fuse the fusible imitation leather composition at the upper and lower parts of the edges so that the same will run over the singed edges and seal the same, as is shown in Figure 3, the heat of the singeing flame being sufficient for this purpose.

In the drawings, there is illustrated an apparatus to aid in carrying out this method, the same comprising a pair of plates 1, each having an area corresponding substantially to the area of the cut blanks. A convenient number of blanks 2, the edges of which it is desired to finish, are stacked in superimposed relation with their edges in alinement between these plates 1, which are then pivotally clamped between the jaw members 3 of a U-shaped clamp 4. A screw 5 is shown adjustably screw-threaded through the upper jaw member 3 to pivotally contact the upper plate. A similar screw or pivot support extends from the lower jaw member so that the plates and blanks therebetween can pivot or rotate on the axis of the pivot screw 5. The U-shaped clamp 4 can be supported in any approved manner and the torch applied to the edges to singe off the tufts or fringes and at the same time heat the composition used, which, if of a fusible nature as previously described, will fuse under said heat and run over the edges and seal the same. The blanks are compressed between the plates by means of the screw 5 and as the plates 1 cover the total area of the blanks, the same will be compressed over their total area so that the fusion of the imitation

leather composition must be confined to the exposed edges and cannot penetrate the compressed area and spoil the blanks.

From the foregoing it will be apparent that I have invented a new method for finishing the raw edges of pyroxylin coated fabric, or imitation leather, that is simple and efficient and have devised a suitable apparatus to aid in preparing said method.

I am aware that numerous details of construction may be varied through a wide range without departing from the principles of this invention, and I therefore do not purpose limiting the patent granted otherwise than necessitated by the prior art.

I claim as my invention:

1. The method of finishing the raw cut edges of fabric blanks treated with a fusible cellulose composition or the like, comprising stacking a plurality of blanks in superimposed relation with their edges in alinement, compressing the same and singeing the edges and fusing the composition for sealing the said edges.
2. The method of finishing the edges of fabric blanks coated and impregnated with

a fusible composition of nitrocellulose or the like, comprising stacking a plurality of blanks in superimposed relation with the edges in alinement, compressing the total area thereof and simultaneously singeing the edges and fusing the composition to seal the edges.

3. The method of finishing the edges of fabric, coated and impregnated with a fusible composition of cellulose or the like, comprising singeing the raw edges and fusing the composition to seal said edges.

4. The method of finishing the edges of fabric blanks treated with a fusible composition for producing imitation leather, comprising singeing the edges to burn off the loose fringes and simultaneously heating the composition for fusing the same to seal the edges.

In testimony whereof I have hereunto subscribed my name in the presence of two subscribing witnesses.

CHARLES R. FARGO.
